FIG. 5

FIG. 6

FIG. 7

FIG. 1 is a side elevational view of a combined archery game projector and shuttlecock projectile showing our new design;

FIG. 2 is an end elevational view thereof as seen from the left of FIG. 1, with the shuttlecock removed for purposes of clarity;

FIG. 3 is an end elevational view thereof as seen from the right of FIG. 1;

FIG. 4 is an enlarged, broken, cross-sectional view thereof taken on line 4—4 of FIG. 1;

FIG. 5 is an end elevational view of the shuttlecock of the archery game apparatus hereof as seen from the right of FIGS. 1 and 4;

FIG. 6 is an enlarged, fragmentary side elevational view of the arrow tip of the combined archery game projector and shuttlecock projectile hereof; and

FIG. 7 is an end elevational view of the arrow tip as seen from the left of FIG. 6.

We claim:

The ornamental design for a combined archery game projector and shuttlecock projectile, as shown.
